UNITED STATES PATENT OFFICE.

REED H. PAGE, OF SLATER, MISSOURI.

VETERINARY SYRINGE.

Application filed April 18, 1924. Serial No. 707,483.

To all whom it may concern:

Be it known that I, REED H. PAGE, a citizen of the United States, residing at Slater, in the county of Saline and State of Missouri, have invented certain new and useful Improvements in Veterinary Syringes, of which the following is a specification:

The present invention relates to a syringe to be used by veterinary surgeons for making injections into animals.

The main object of the invention is to provide a syringe which may be attached directly to a bottle or container holding the serum or medicine to be used on an animal.

15 A syringe attached in this manner is adapted to be filled directly from the bottle and then immediately used on an animal. It is evident that a great number of animals may thus be treated one after the other and the 20 syringe filled as required from the bottle.

The syringe is provided with a stem carrying double graduations so that a direct reading may be made indicating the dose to be used on the animal and simultaneously 25 the quantity of medicine still contained in the syringe.

In the accompanying drawings, one embodiment of the invention is illustrated, and Figure 1 is a side elevation of the syringe 30 with a bottle attached;

Figure 2 is a longitudinal section of Figure 1 with the bottle removed, and

Figure 3 is a longitudinal section of some 35 of the details.

In the drawings, reference numeral 10 represents a bottle containing serum or other medicine which is to be injected into an animal. The neck 11 of the bottle is closed by a stopper or cork 12 in the usual 40 manner and in this stopper is fitted a tube 13 extending through the same in both directions. The inner end of the tube is pointed, as at 14, and has a longitudinal aperture 15 running across the pointed end. The 45 tube has a collar 16 adapted to engage with the stopper to limit the movement of the tube into the bottle.

Reference numeral 17 represents a carrier for the bottle having a main shank 18 extending along the side of the same and provided with ratchet teeth 19 at its rear end. These teeth are adapted to engage with a spring ratchet dog 20 which is mounted in a slide 21 enclosing the shank 18, as best 55 seen in Figures 1 and 3. The slide 21 has on one side a cup-shaped base 22 adapted to

engage the butt end of the bottle and it is evident that by shifting the said slide back and forth on the shank 18 the carrier may be adjusted to bottles of different lengths. 60 The forward end of the carrier 17 has a cup-shaped cover 23 adapted to fit over the mouth of the bottle as indicated in Figure 1. It is evident that with the bottle in position and the carrier adjusted to fit tightly 65 over the butt end and mouth of the bottle, the stopper will press the collar 16 of the tube 13 tightly against the inner wall of the cover 23 and retain the tube in fixed position. 70

To the inclined portion of the carrier 17 is rigidly secured a cylindrical casing 24 which has a longitudinal opening 25 along one side thereof and at the opposite side a small window 26 so that the amount of material in the syringe can easily be ascertained through the same. A glass cylinder 27 fits snugly inside the casing 24 and is retained in position between a cap 28 and a head 29, the former being threaded externally upon the rear end of the casing, and the latter being brazed internally to the forward end thereof. Between the cap 28 and the glass cylinder 27 is inserted a leather or rubber gasket 30 and similarly 80 between the head 29 and the cylinder 27 is inserted another rubber or leather gasket 31. In this manner a tight joint is formed 85 at each end of the syringe so that no serum or medicine contained therein can escape at 90 either end through the joints.

At the forward end of the head 29 is inserted an outlet nozzle 32 having threaded engagement therewith, and this nozzle communicates with a channel or port 33 in the head 29 for passing the medicine from the glass cylinder 27 into the body of the animal. In this port is provided a valve 34 which is adapted to have two positions, one to permit flow of the medicine through the 95 port from the cylinder to the nozzle and the other to close the outlet to the nozzle and simultaneously open communication from the interior of the casing in transverse direction to a port 35. A feed tube 36 of elbow shape is screwed into the head 29 at the port 35 and has its outer end fitting tightly in the end of the tube 13, as best seen in Figure 2.

In the cap 28 a stem 37 is adapted to 110 slide in axial direction. The stem is provided with a convex handle 38 fitting the

22
 palm of the operator's hand and is held in position on the square end 39 of the stem 37 by means of a screw or nut 40, as best seen in Figure 2. The stem 37 is threaded 5 practically its entire length and carries a gage nut 41 between the handle 38 and the cap 28.

On the inner end of the stem 37 is carried a piston 42 which is preferably made from 10 soft rubber and has an annular groove 43 around it. This piston abuts against a retaining washer 44 held in position by a head 45 formed on the end of the stem 37. At the rear end of the piston 42 is shown a 15 compression disc 46 which is threaded on the stem 37 and which tends to compress the rubber piston 42 when screwed up tightly against the same. The rear end of the disc has a square sectioned boss 47 which is 20 adapted to engage in a correspondingly shaped recess 48 in the cap 28. It is evident that when the piston is retracted all the way up against the cap 28, the square sectioned boss 47 will engage in the recess 48 25 and by then turning the handle 38 it is possible to tighten or loosen the disc 46 against the rubber piston 42 to obtain a suitable grip between the same and the interior of the glass cylinder 27. Along one side of the 30 stem 37 is furnished a flat surface which is provided with two scales, one commencing at zero near the piston 42 and the other commencing at zero under the handle 38. In this manner it is possible to read from 35 both ends of the stem and to ascertain without computation how much of the medicine has been taken out of the syringe and how much is left.

On the head 29 is provided two stops and 40 for the valve 34 so that when the valve is turned in one direction communication is opened between the interior of the syringe and the nozzle 32, while when the valve is turned in the other direction until its handle 45 abuts against the other stop, communication will be opened between the interior of the 50 syringe and the bottle 10.

On the outside of the casing 24 is mounted a finger grip 53 facilitating the operation 55 of the syringe. The operator places the handle 38 in the hollow of his hand and lays one of his fingers over the grip 53 and in this manner the pushing down of the stem 37 is easily accomplished.

In using the device the bottle 10 containing the serum or other medicine is clamped in position on the carrier 17 between the cover 23, engaging the mouth of the bottle, and the base 22, engaging the butt end 60 thereof. By pushing the base forwardly as far as it will go the slide 21 will follow and the ratchet dog 20 will engage in a suitable tooth on the shank 18 and hold the bottle securely thereon. Before the bottle is 65 secured in this manner the stem 37 of the pis-

ton 42 should be pushed into the syringe as far as it will go. The valve 34 is next turned to open communication between the tube 13 and the interior of the syringe. The stem is now drawn out of the syringe until the 70 piston is stopped by the cap 28 and the syringe is then filled. The valve 34 is next turned until the port 35 is closed and communication is opened to the nozzle 32 from the interior of the syringe. 75

The gage nut 41 is thereupon screwed down on the stem 37 to indicate on the scale commencing near the piston, the size of the dose to be given the animal. The scales are preferably laid out in cubic centimeters. If, for 80 instance, a dose of five cubic centimeters of serum is to be injected into the animal, the gage nut 41 is set at five cubic centimeters thus forming a stop at that point on the scale and the syringe applied to the animal. 85 By taking hold of the grip 53 and the handle 38, the operator pushes the stem 37, with the piston 42, forwardly until the gage stop abuts against the cap 28 and this amount of serum will have been injected into the animal. If, however, the animal breaks and runs away before the full dose has been given to it, the operator can easily ascertain on the scale at the rear end of the cap, 90 the amount that has been administered to the animal. The remainder of the dose being the difference between said reading and that for which the gage is set will accordingly have to be injected a second time into the animal. 95

100 Although the device is primarily designed as a veterinary syringe, it is evident that the construction adapts itself equally well to hypodermics of all kinds.

It should be noted that the carrier 17 will 105 permit the use of different sized bottles both as regards length and diameter. The cup-shaped base will always center the butt end of the bottle correctly in relation to the cover 23, and the ratchet device takes care 110 of the length of the bottle.

The valve 34 and the feed tube 36 are each 115 provided with fairly large openings permitting quick filling of the syringe.

Having thus described the invention, 115 what is claimed as new is:

1. In a device of the character described, a cylinder, a head at one end of said cylinder formed with inlet and discharge ports, a piston slideable longitudinally in said cylinder, a reservoir carrier including a strip extending longitudinally of said cylinder and having a portion secured to the cylinder and a portion extending in spaced relation to the rear end of the cylinder, a cover 120 extending from said strip to engage the forward end of a reservoir and provided with an opening, a conduit passed through the opening and having its rear end portion adapted to extend into the reservoir and 125 130

its forward end in communication with the inlet port of said head, and means carried by the free portion of said strip and adjustable longitudinally thereof into position to engage the rear end of the reservoir and hold the reservoir in place.

2. In a device of the character described, a cylinder, a head at one end of said cylinder formed with inlet and discharge ports, 10 a piston slidable longitudinally in said cylinder, a reservoir carrier including a strip extending longitudinally of said cylinder and having a portion secured to the cylinder and a portion extending in spaced 15 relation to the rear end of the cylinder, a cover extending from said strip to engage the forward end of a reservoir, a conduit communicating with the inlet port of said head and adapted to extend into a reservoir 20 engaged by said cover, and a base adjustable longitudinally upon the free portion of said strip into position for engagement 25 with the rear end of the reservoir to securely clamp the reservoir between the base and cover.

3. In a device of the character described, a cylinder, a head at one end of said cylinder formed with inlet and discharge ports, a piston slidable longitudinally in said cylinder, 30 a reservoir carrier including a strip extending longitudinally of said cylinder and having a portion secured to the cylinder and a portion extending in spaced relation to the rear end of the cylinder, a cover 35 extending from said strip to engage the forward end of a reservoir, a conduit communicating with the inlet port of said head and adapted to extend into a reservoir engaged by said cover, and a base adjustable longitudinally upon the free portion of said strip 40 into position for engagement with the rear end of the reservoir to securely clamp the reservoir between the base and cover, said base being concaved whereby a reservoir 45 engaged by the base will be automatically centered thereon.

4. In a device of the character described,

a cylinder, a head at one end of said cylinder formed with inlet and discharge ports, 50 a piston slidable longitudinally in said cylinder, a reservoir carrier including a strip extending longitudinally of said cylinder and having a portion secured to the cylinder and a portion extending in spaced relation to the rear end of the cylinder, a 55 cover extending from said strip to engage the forward end of a reservoir, a conduit communicating with the inlet port of said head and adapted to extend into a reservoir engaged by said cover, a base adapted 60 to engage the rear end of a reservoir, a guide carried by said base and slidable along the free portion of said strip, and means to secure said guide in a set position upon said strip.

5. In a device of the character described, a cylinder, a head at one end of said cylinder formed with inlet and discharge ports, a piston slidable longitudinally in said cylinder, a reservoir carrier including a strip 70 mounted at one side of said cylinder and having a portion attached to said cylinder longitudinally thereof and a portion extending in diverging relation to the rear end of the cylinder and provided with ratchet 75 teeth, a cover extending from the said strip to engage the forward end of a reservoir and provided with a depending peripheral flange and with an opening, a base adapted to engage the rear end of the reservoir and 80 provided at one side with a guide sleeve slidably mounted upon the rear end portion of said strip, a latch carried by said guide and adapted to engage the teeth of said strip to retain said base in a set position for 85 clamping engagement with the rear end of the reservoir, and a conduit passed through the opening in said cover and having its rear end portion adapted for insertion into the reservoir and its forward end communicating with the inlet port of said head.

In testimony whereof I affix my signature.

REED H. PAGE.
